United States Patent Office

Des. 217,955
Patented July 7, 1970

217,955

CONTAINER CAP

John R. Howard, Lombard, and Conrad Thatcher Schwartz, Jr., Wheaton, Ill., assignors to Container Corporation of America, Chicago, Ill., a corporation of Delaware

Filed June 2, 1969, Ser. No. 17,443

Term of patent 14 years

Int. Cl. D9—02

U.S. Cl. D9—284

FIG. 1 is a perspective view of a container cap, showing our new design;

FIG. 2 is a side elevational view thereof;

FIG. 3 is a top plan view thereof; and

FIG. 4 is a bottom plan view thereof.

We claim:

The ornamental design for a container cap, as shown.
